CLAIM

We claim the ornamental design for a transparent clip-style balloon weight, as shown and described.

DESCRIPTION

FIG. 1 is a perspective view of a transparent clip-style balloon weight showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The broken line showing of the spring is included for the purpose of illustrating a portion of the transparent clip-style balloon weight that forms no part of the claimed design.
